UNITED STATES PATENT OFFICE.

BENJAMIN SCHUMSKY, OF PHILADELPHIA, PENNSYLVANIA.

DESIGN FOR A SCHOOL-COMPANION.

48,695.

Specification for Design.

Patented Mar. 7, 1916.

Application filed November 13, 1915. Serial No. 61,438. Term of patent 7 years.

To all whom it may concern:

Be it known that I, BENJAMIN SCHUMSKY, a citizen of the United States, residing at Philadelphia, in the county of Philadelphia and State of Pennsylvania, have invented a new, original, and ornamental Design for School-Companions, of which the following is a specification, reference being had to the accompanying drawing, forming a part thereof.

The figure is a view in front elevation of a school companion, showing my new design. I claim.

The ornamental design for a school companion, as shown.

BENJAMIN SCHUMSKY.

Witnesses:

MARIE JACKSON,
CHAS. E. POTTS.
